UNITED STATES PATENT OFFICE.

FRANK MIHAUT, OF PETERSBURG, VIRGINIA, ASSIGNOR TO ALBINA MIHAUT, OF PETERSBURG, VIRGINIA.

COMBINED PEANUT-VINE CLEANER AND CONVEYER.

Application filed September 28, 1922, Serial No. 591,146. Renewed March 3, 1925.

To all whom it may concern:

Be it known that I, FRANK MIHAUT, a citizen of the United States, residing at Petersburg, in the county of Dinwiddie and State of Virginia, have invented certain new and useful Improvements in Combined Peanut-Vine Cleaners and Conveyers, of which the following is a specification.

The present invention consists of a combined peanut vine cleaner and conveyer which is adapted for attachment to a peanut threshing machine.

The principal object of this invention is to effectively clean the peanut vines by mechanical means, without the intervention of manual effort, and to conduct the cleaned vines to a predetermined point.

A coordinate object of the invention is to incorporate suitable bridging means in the cleaning mechanism to deflect the vines from the conducting mechanism, permitting the vines to pass from the cleaning mechanism directly onto the ground to permit re-threshing of the vines or allow for any other disposal of the same.

The above and other objects of this invention will be understood from the following description of the present preferred embodiment of the invention taken in connection with the accompanying drawings wherein:

Fig. 1 is a side elevational view of the combined vine cleaner and conductor constructed in accordance with this invention illustrating the application of the same on a peanut threshing machine;

Fig. 2 is a vertical sectional view of the vine cleaner per se;

Fig. 3 is a longitudinal sectional view of the combined vine cleaner and conductor; and

Fig. 4 is a horizontal sectional view of the combined vine cleaner and conductor.

In the drawings, in order to illustrate the application of this invention a portion of a threshing machine 5 is shown which may be of the usual or any desired construction. In the present instance the rear end of the threshing machine is shown to be of standard configuration and has the endless conveyer attachment removed therefrom leaving sufficient space at the rear end of the thresher for the accommodation of my improved vine cleaner and conductor generally designated 6. The invention is secured

to the thresher in any suitable manner such for instance as by metal straps 7 and 8. The invention consists especially of parallelly arranged horizontal supporting beams 9 which are mounted upon the straps 8. 60 These beams have a superstructure 10 arranged thereon which in the present instance consists of a pair of parallel boards or plates 11 which are inclined and are arranged to dispose their inner ends adjacent 65 the outlet end of the threshing machine. The boards 11 have a screen 12 secured to the upper margins thereof said screen being clamped into engagement with the boards 12 by bars 13. The bars 13 are arranged 70 above and are secured to the boards 11 in any desired manner. Upon reference to Fig. 4 of the drawings it will be apparent that the screen 12 extends from one board 11 to the other and extends the complete 75 lengths of the boards.

Each of the bars 13 carries a pair of bearing plates 14, the bearing plates of one bar being in parallelism with the bearing plates of the opposite bar, each pair of parallel 80 plates having the ends of a shaft 15 journaled therein. Each of said shafts carries a sprocket wheel 16 adjacent to the inner face of each of the bearings 14, said wheels being engaged with the sprocket chains of an 85 endless conveyer 17. The endless conveyer includes slats 18 which extend transversely across from one sprocket to the other said slats being adapted for wiping contact over the upper surface of the screen 12 in order 90 to keep the latter free from the accumulation of dust or other extraneous materials. The conveyer may be actuated by engagement of a power belt 18' with a pulley 18. The power belt may be engaged with a 95 source of energy on the threshing machine if so desired.

Walls 19 rise upwardly from the beams 9 and have the upper margins thereof disposed at an inclination and engaged with a 100 top 20. In this way a casing is provided for the cleaning mechanism which casing is open at the front to permit the entrance of the peanut vines directed thereinto from the threshing machine. The rear of the 105 casing has the lower end thereof closed as indicated at 21, but the upper end thereof above the apex of the conveyer 17 is open, as indicated at 22.

Depending from said casing top 22 are a 110

plurality of flexible baffles 23 one of which is preferably arranged so that its lower marginal edge will be in surface contact with the upper run of the conveyer 17 adjacent the front end of the latter. The other baffle is preferably arranged so that its lower marginal edge will be in surface contact with the upper run of the conveyer about midway the ends of the latter. In the present instance the baffles are preferably made of canvas against which the peanut vines will be projected from the thresher. These baffles will be sufficiently stable to cause the peanut vines to drop on to the conveyer 17, but at the same time will be flexed sufficiently to yield under pressure. In order to convey the peanut vines to some predetermined point, after the vines have passed to the end of the conveyer, a suitable conductor mechanism is provided. This conductor mechanism includes a chute 24 the lower end of which is formed to provide a channel or trough 25. The chute and channel preferably consist of an integral metallic sheet the upper edge of which is engaged with the bars 13 and is supported by the latter. One end of the channel or trough 25 communicates with an opening 26 through which the peanut vines are drawn by the suction of a fan 27. The fan 27 is mounted in a suitable casing 28 arranged on one of the side walls 19. The casing 28 has a conveyer tube 29 issuing therefrom which may be of any desired length so that the outlet ends will be positioned at any desired point remote from the thresher. The fan 27 is operated through the instrumentality of a power belt, operated by the thresher or by any other suitable power means engaged with the fan pulley 30.

At times it may be necessary to divert the peanut vines to allow the same to be re-threshed or to permit some other disposition to be made of the same. Consequently, I have provided suitable means whereby the vines may be instantly diverted from the conductor mechanism when desired by the operator. This mechanism consists of a bridge board 31 preferably of oblong shape and having the ends thereof arranged to lie in close proximity to the sides 19. One of the lateral margins of the boards is equipped with a rod 32 the ends of which rod are journaled in the sides 19. The rod is fixed to the bridge board 31 so that rotation of the rod will correspondingly actuate the bridge board. In order to facilitate rotation of said rod a knob 33 may be mounted on one end thereof. Also, in order to hold the bridge board in an inoperative position, such as indicated by the dotted lines 33, a pawl and ratchet mechanism may be employed, in which instance a ratchet 34 may be mounted upon the rod 32 and a pawl 35 pivotally mounted on one of the sides 19 in

proximity to the ratchet wheel 34 to engage the latter. When it is desired to lower the bridge board into the position shown in Fig. 3, the pawl may be disengaged. When the bridge board is in the position shown in Fig. 3 of the drawings the peanut vines carried by the conveyer will pass over the bridge board through the opening 22 and onto the ground.

In use of this device the peanut vines are projected from the thresher to the conveyer in a manner heretofore described. The conveyer carries the vines to the chute 24 and the vines are permitted to gravitate downwardly on said chute into the channel or trough 25. During this cycle of operation the dust and other extraneous materials, which usually accompany the peanut vine and are so obnoxious to attendants conveying the peanut vines, will be permitted to gravitate downwardly through the slats 18 and through the screen 12 on to the ground. Of course, the screen prevents the passage of any of the vines therethrough and the screen is constantly cleansed by the engagement of the slats 18 of the conveyer therewith. In this way, the peanut vines are thoroughly cleaned and may be conveyed to any predetermined point without the intervention of manual assistance. This is important in view of the well known undesirable characteristics of the peanut and allied vines which although very desirable as an animal food are undesirable to handle because of the dust and other foreign particles accompanying the same.

It is of course to be understood that various changes may be made in this device especially in the details of construction, proportion and arrangement of parts within the scope of the claims appended hereto.

What is claimed is:—

1. A peanut vine cleaner for threshing machines including a casing equipped with an inclined screen the lower end of which is arranged in proximity to the outlet end of the thresher, an endless conveyer movable above said screen and including slats which wipe over the latter, and fabric baffles depending from the top of said casing above the conveyer to be impinged by materials passing from the thresher substantially as described.

2. A combined peanut vine cleaner and conveyer including a casing, a vine conveyer operatively mounted in said casing, a chute depending downwardly from the discharge end of the conveyer, a conductor in communication with said chute to catch vines gravitating from the latter, one end of said casing having an opening therein, a bridge board normally extending across the opening and being movable into a position across the top of the chute and extending from the discharge end of the conveyer to said

casing opening to deflect the vines from the chute directly through said casing opening.

3. A combined peanut vine cleaner and conductor including a casing equipped with 5 cleaning mechanism, the lower rear end of said casing being closed and equipped with vine conductor mechanism, and deflecting mechanism operable to prevent passage of said vines into said conductor mechanism 10 and to deflect said vines through the rear end of the casing, above said closed part of the latter.

4. A combined peanut vine cleaner and conveyer including a casing equipped with a screen supporting structure, a vine conveyer movable across said screen, a chute depending from one end of the supporting structure and comprising a metal sheet the lower end of which is formed to provide a trough, one side of said casing having an 15 opening therein which communicates with one end of the trough, and a vine conductor communicating with said opening.

FRANK MIHAUT.
